UNITED STATES PATENT OFFICE.

W. BILLINGS RICE AND MERRIT H. RICE, OF NEW YORK, N. Y., ASSIGNEES
OF ONE-HALF TO WILLIAM D. CAMERON, OF SAME PLACE.

MACHINE FOR CRUSHING ORE, STONE, &c.

SPECIFICATION forming part of Letters Patent No. 328,144, dated October 13, 1885.

Application filed March 17, 1885. Serial No. 159,164. (No model.)

To all whom it may concern:

Be it known that we, W. BILLINGS RICE and MERRIT H. RICE, both of the city of New York, in the county and State of New York, have invented certain new and useful Improvements in Machines for Crushing Ore, Stone, &c., of which the following is such a full, clear, concise, and exact description as will enable others skilled in the art to which our invention appertains to construct and use the same, reference being had to the accompanying drawings, forming part of this specification.

The object of our invention is to construct a machine for crushing ore, stone, and other material of like character, or susceptible of having a similar operation performed upon it, and in the construction thereof to employ compound-lever mechanism in connection with such other parts as may be desirable or adapted to the purpose, whereby the required pressure may be exerted upon the ore or other material to be crushed, comminuted, or pulverized.

In the drawings, Figure 1 is a vertical cross-section of a crushing-machine provided with three sets of engaging jaws and two pairs of pulverizing rollers or cylinders, all of which appear in this figure. Fig. 2 is a horizontal cross-section taken on line *x x*, Fig. 1, showing the arrangement of the lever mechanism and other parts which operate the engaging jaws and rollers made to act upon the material to be crushed. Fig. 3 is a vertical side view of the machine, partly in section. Fig. 4 is a side view, partly in section, of a modification of the arrangement of the shafting which actuates the lever mechanism, and showing also means which may be employed to give different speed to the several pairs of crushing-jaws, whereby the speed of each pair succeeding the first is increased over that of the preceding pair.

In the drawings, A represents the frame of the machine, and *a* the hopper through which the material is fed to the machine.

B represents a shaft, which should be located in a position which will admit of the connection of the lever C to it, and from which lever C a rod, D, may extend to and be connected with a crank-shaft, or crank formed in a shaft, as indicated by dotted lines, Fig. 2,

which shaft may be operated by a pulley, and so made to actuate the rod D, which in turn imparts motion to the lever C and to the shaft B.

In Fig. 4 the rod D is shown as being actuated by a fly-wheel, D', secured upon a shaft or bearing having a pulley secured thereto, which pulley connects by belting with still another pulley upon another shaft, as shown in this figure.

To the shaft B a rocking lever, E, having two arms is secured, so that the arms thereof extend in such a direction as to admit of their being connected by intermediary arms, *b b*, to one of the arms of each of two elbow-levers, F F, as at *c c*. The other arms of the elbow-levers F F are united together by a knee or toggle joint, *d*, and the elbows thereof connected, as by a socket-joint, *e*, to working-levers G G, made to bear upon the engaging jaws H H by being fulcrumed in sockets *f f* in portions of the frame. Instead, however, of having the knee or toggle joint *d* made to unite the arms of the elbow-levers F F, these arms may respectively be connected to the working-levers G G, as at *e e*, and the elbows of such levers should in that case be united by a knee or toggle joint, which, while reversing the position of the elbow-levers from that shown in the drawings, as respects their position with each other, would nevertheless produce precisely the same result. It is desirable to make the joint which unites the elbow-levers together, so that the ends or parts which are thereby united shall form semi-cylindrical concavities moving or bearing upon a corresponding convexity or bearing-pin, which may be made to form a part of such joint.

The engaging jaws H H are preferably made so as to form no part of the system of connecting-levers, and may be pivoted or hinged in sockets made in portions of the frame, as at *h h*, and hung in such position as that the working-levers G G will, when the lever mechanism is actuated, be made to bear upon them, and so compel such engaging jaws to seize and crush the material fed into the machine or between such jaws. These jaws should of course be made strong enough to stand the strain to which they are necessarily subjected.

We prefer to arrange the lever mechanism

and the engaging jaws so that one pair of jaws and its corresponding lever mechanism shall be at the upper part of the frame-work, and so that the lever mechanism shall move in a horizontal plane. Beneath this the next pair of engaging jaws are set in the machine, with its lever mechanism working in a horizontal plane below the first set. In like manner a third pair of engaging jaws and its lever mechanism may be placed still lower in the framework of the machine, and so on until the desired number of sets are secured in place. The first or upper pair of engaging jaws are placed just beneath the hopper or mouth of the machine, and these jaws are preferably set farther apart than the pair just beneath them. The jaws of the second pair may be farther from each other than the ones just below, and so on until the series is completed.

20 The lever mechanism for operating the several pairs of engaging jaws can operate by one shaft, as shown in Fig. 3; but it may be desirable to employ counter-shafts for giving greater speed to the lower pairs of jaws than would be required for the upper one, the speed being made to increase with each succeeding pair. The reason for this is apparent, inasmuch as the upper pair would simply break the stone or ore, which drops to the jaws below in a greater number of pieces, each of which must be crushed, requiring a more active operation, in order that there may be no clogging.

30 The arrangement of the shafting to which the lever mechanism for operating the several pairs of engaging jaws is connected (shown in Fig. 4) is very well adapted, when connected, as therein shown, with the other mechanism for operating such shafting, to produce the 40 requisite speed for each pair of engaging jaws. In this figure the shafting which operates the lever mechanism is shown as being divided into sections B B' B'', separated from each other by bearings b'. In the upper section the 45 rod D is shown as being connected to a fly-wheel, D', which has its bearing upon a shaft passing through a brace, and having a pulley-wheel connected to the other end thereof. The same arrangement is employed for each 50 succeeding pair of engaging jaws, with the exception that the pulley upon the shafting to which the fly-wheel for each succeeding pair is secured is in each case smaller than the pulley which operates the fly-wheel next 55 above it. These several pulleys may be belted, as shown, with other pulleys upon a shaft still farther away, which may be located in any convenient part of the machine; but the pulleys upon such shaft diminish in size in inverse 60 order from those which operate the several fly-wheels, or may be arranged according to the speed required for each pair of engaging jaws. The mechanism for operating each set of jaws may, however, be operated by an independent shaft of its own, if desired.

65 In crushing material which needs to be pulverized or reduced to a very fine degree

of comminution, one or more pairs of rollers or cylinders, I I, of any desired diameters and lengths, and made of iron, steel, or other material sufficiently hard and strong for the purpose, may be placed in the machine beneath the crushing-jaws, as shown in the drawings, Figs. 1 and 3. These rollers may be operated by the gearing J, or by any other desired means.

It is obvious that the machine may be constructed with but a single pair of engaging jaws, if it is intended simply to break stone into pieces of some magnitude; or it may have any number of pairs of engaging jaws, and the rollers may or may not be used, according to the requirements of the work to be performed.

The operation of the machine will readily 85 be understood. The shaft B, when set in motion, actuates the arms of the levers E, which by their connection with the elbow-levers F cause them to spread or contract, so that their elbows actuate the levers G G upon 90 their fulcrums f f, and their extremities are thereby made to bear upon the jaws H H, which come in contact with and crush the material fed to the machine.

Inasmuch as we have already prepared an 95 application for a patent in which we claim compound-lever mechanism, practically such as that which is here adapted to operate the engaging jaws, and as ordinary rollers have heretofore been used for pulverizing or 100 comminuting different materials, we do not intend to claim herein the compound-lever mechanism simply; but

What we do claim, and desire to secure by Letters Patent, is—

105

1. In a machine for crushing ore, stone, &c., the lever E, fulcrumed on a shaft, and elbow-levers F F, connected therewith, and also united together by a knee or toggle joint, in combination with working-levers G G and engaging jaws H H, such working-levers being adapted to move the engaging jaws toward each other, whereby they may be made to crush the material, substantially as described.

2. In a machine for crushing ore, stone, &c., 115 a series of two or more pairs of engaging jaws, and working-levers G G, adapted to work each jaw of the several pairs, in combination with elbow-levers F F, united by a knee or toggle joint, and rocking lever E, fulcrumed 120 upon a shaft and connected with said elbow-levers, substantially as described.

3. A machine for crushing ore, stone, &c., provided with a series of two or more pairs of engaging jaws, compound-lever mechanism for operating the same, and means for giving to the levers which operate each pair of jaws succeeding the first more rapid action than is given to the levers which operate the preceding pair, whereby the several 130 pairs of engaging jaws may be made to keep pace with each other in crushing the material to different degrees of comminution, substantially as described.

4. In a machine for crushing ore, stone, &c., shaft B, lever-arm C, secured thereto, rod D, connected with said arm, and crank or fly-wheel D', connected with said rod, in combination with rocking lever E, secured to the shaft B, elbow-levers F F, united together and connected with said rocking lever, working levers G G, and engaging jaws H H, arranged and operating substantially as described.
